PAINT BRUSHES

Jens Oscar Larsen, Lisleby per Fredrikstad, Norway
 Application March 3, 1958, Serial No. 718,707
 Claims priority, application Norway March 23, 1957
 2 Claims. (Cl. 15—193)

The present invention relates to a paint brush, and the object of the invention is to provide a paint brush of simple construction and which is particularly suited for non-professional work.

Another object of the invention is to provide a paint brush which is of light weight in relation to its size.

Paint brushes at present on the market are manufactured by inserting the bristles with their root end in a ring or open container and secured in same by vulcanisation, whereafter the container is closed by means of a lid or a plug having a handle.

In this procedure bristles of such a quantity that the container will be approximately filled has to be used to produce a brush with uniform bristles.

With the improvement in accordance with the invention the brush container is provided with a perforated base member, so that only a fraction of the cross section of the container is open for reception of bristles. With an appropriate position of the perforations or openings in the container, a uniform distribution of the bristles will, however, be achieved in spite of the fact that substantially less bristles are required for filling of the openings in the base member than is the case when using containers without perforated members.

In accordance with the invention the openings in the base member may preferably be arranged as concentric annular slots with approximately radially extending connections between the different parts of the base member and between the base member and the side walls of the container.

In a simple embodiment of the invention the perforated base member is arranged in alignment with the lower or outer edge of the container. This will, however, in certain cases involve difficulties, as paint which collects at the root of the bristles will tend to drip from the brush. In the same manner the connections between the base member and the container will, if the connections are positioned level with the edge of the container cause the bristles to diverge at this position when viewed from the side.

This disadvantage is in accordance with this invention eliminated by the feature that the base member of the container is positioned somewhat inside the container in relation to its outer edge, so that the side wall of the container will form a ring around the outer edge of the base member of the container. Similarly the connections between the base member and the container and the side wall of same and between the different parts of the base member are positioned at a distance from the outer edge of the container, so that the bristles will not diverge at these points.

Principally the invention thus concerns an improvement in paint brushes of the kind comprising a container for insertion and attachment of the bristles, and a cover and handle attached to said container, and the invention is characterized in that the container is provided with a base member having a number of slots or perforations forming guides for the bristles extending out from the container.

A further feature of the invention consists in that the base member of the container is positioned inside the container, thus forming a rim surrounding the base member around the outer side of same.

5 The invention may further be characterized in that the base member of the container is attached to the inner side by means of connections which from the free circumference of the base member extend radially into a container, and are attached to the side walls of the container further inside same than the base member of the container.

Other objects and advantages of my invention will become more apparent from a study of the following specification and the accompanying drawings, in which:

Fig. 1 is a longitudinal sectional view of a paint brush of the circular type according to one embodiment of my invention; and

Fig. 2 is a sectional view taken along line 2—2 of Fig. 1.

20 Referring now to the drawings, the paint brush handle 1 has a cylindrical flange or cover portion 2 which is mounted within one end of the cylindrical sleeve or container 3. Mounted transversely within the sleeve 3 intermediate its ends is the base member 9 which consists of an inner circular plate 9' and an annular plate 9'' arranged coaxially intermediate and spaced from the circular plate 9' and the inner circumference of the sleeve 3. The inner base plate 9' is connected to the outer annular plate 9'' by means of the radial connecting members 15 and the outer annular plate 9'' is connected to the sleeve 3 by means of the radial connecting members 13. Thus the annular space 10 is provided intermediate the sleeve 3 and the plate 9'', and annular space 11 is provided intermediate the plate 9'' and the plate 9'.

25 Extending within the annular spaces 10 and 11 in the base member 9 are the brush bristles 4 the upper ends of which are rigidly maintained in place by means of the solid, rigid body 5 of vulcanized material. By means of this improvement it is possible to use less bristles for the achievement of a good result than provided by brushes having no such base member.

30 The sleeve 3 projects downwardly beyond the base plate 9 to provide a rim portion 12 which surrounds the outside periphery of the bristles 4.

35 As shown in Fig. 1 the connecting members 13 and 15 have horizontal rib portions axially offset in the direction of the brush handle 11 by the vertically extending portions 13' and 15', respectively. Thus the annular slots 10 and 11 will be uninterrupted in the plane of the base plates 9' and 9'' and the bristles will emerge in continuous arrangement from the lower end of the sleeve 3. Rim portion 12 serves to prevent radial outward divergence of the bristles in the outer periphery of the brush.

40 While I have illustrated and described the preferred circular brush type of embodiment of my invention, it will be apparent to those skilled in the art that other changes and embodiments may be made in the product disclosed without deviating from the scope of my invention as defined in the accompanying claims.

I claim:

45 1. A paint brush comprising a vertical cylindrical container sleeve, a paint brush handle secured to the upper end of said sleeve, a circular base plate coaxially arranged horizontally within said sleeve intermediate the ends thereof, at least one annular plate coaxially arranged in the same plane as said circular base plate intermediate and spaced from the periphery of said circular base plate and the inner periphery of said sleeve, a plurality of connecting members connecting said circular base plate to said annular plate and said annular plate to said sleeve, said connecting members each having vertical portions extending upwardly from said plates and horizontal rib por-

tions axially offset within said sleeve from the plane of said plates in the direction of said brush handle to provide continuous uninterrupted annular openings between said plates and between said annular plate and said sleeve, a plurality of bristles arranged continuously within said annular openings, the lower ends of said bristles extending downwardly beyond the lower edge of said sleeve and the upper ends of said bristles extending above the plane of said circular base plate and said annular plate, and means within said sleeve intermediate said circular base plate and said annular plate and the upper end of

10
5

said sleeve for securing the upper ends of said bristles to said sleeve.

2. A paint brush as defined in claim 1 wherein said means for securing the upper ends of the bristles to said sleeve comprises a layer of vulcanized material.
